UNITED STATES PATENT OFFICE.

ERVIN E. STRAWN, OF DES MOINES, IOWA, ASSIGNOR TO THE OMNIGRAPH COMPANY, OF DES MOINES, IOWA, A CORPORATION.

PRINTING-PLATE HOLDER.

1,392,896.

Specification of Letters Patent.

Patented Oct. 4, 1921.

Application filed January 31, 1921. Serial No. 441,407.

To all whom it may concern:

Be it known that I, ERVIN B. STRAWN, a citizen of the United States, and a resident of Des Moines, in the county of Polk and State of Iowa, have invented a certain new and useful Printing-Plate Holder, of which the following is a specification.

The object of my invention is to provide a printing plate holder adapted to be used in combination with a printing roller designed to travel at a high rate of speed, the parts being of simple, durable and comparatively inexpensive construction.

More particularly my invention relates to a holder for printing plates, which is of comparatively thin and light material, the parts being so arranged that the printing plate may be held flat against the surface of the printing roller and at the same time under tension.

Still another object of my device is to provide a printing roller having means thereon adapted to engage a printing plate, part of said means being capable of longitudinal movement so that when a printing plate is placed thereon, it may be moved for drawing the printing plate taut and against the surface of the printing roller.

Still another object is to provide pins on a printing roller for engaging a printing plate and for holding it thereon against accidental displacement, a part of said pins being adjustable, so that after the printing plate is placed in position, said pins may be adjusted for drawing the printing plate against the surface of the printing roller, and each of said pins having one of its sides tapered, so as to prevent the removal of the printing plates when the pins are in one position.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a side elevation of a printing roller with my improved device shown thereon.

Fig. 2 is an end elevation of the same, parts being broken away and shown in section to better illustrate the construction.

Fig. 3 is a detailed, sectional view taken through one of the adjustable segment members, showing it in engagement with a printing plate; and

Fig. 4 is a vertical, sectional view taken through one of the segment members, showing the tapered side of the pin.

In the accompanying drawings, I have used the reference numeral 10 to indicate an ordinary printing roller, which is provided with a shaft 11. The printing roller 10 is provided at each of its ends with a shoulder 12. One end of the printing roller adjacent to the shoulder 12 is provided with an annular groove 13, so as to form a contracted portion 14, in which is received a plurality of segment members 15.

The segment members 15 have their outer surfaces flush with the outer surface of the main body portion of the printing roller 10 and have their inner surfaces rest against the outer surface of the contracted portion 14. The segment members 15 are of less width than the width of the groove 13, as illustrated in Figs. 1 and 3 of the drawings.

In order to hold the segment members 15 in the groove 13, I have provided bolt devices 16, which are provided with a screw-threaded portion 17 and a contracted portion 18 at their inner ends. The contracted portion 18 is received in an opening 19 in the wall of the groove 13.

The bolt 16 adjacent to the screw-threaded portion 17 is provided with a slightly enlarged portion 20, which is received in an opening 21 formed in the outer wall of the groove 13. A head 21 is formed on the extreme outer end of the bolt 16 and the head is provided with a series of small openings 22 adapted to receive one end of a pin or the like, which may serve as a lever for rotating the bolt 16 within its bearings.

The segment members 15 are provided with a screw-threaded opening 23, which receives the screw-threaded portion 17 of the bolt 16.

From the construction of the parts just described, it will be seen that rotation of

the bolt devices 16 will cause the segment members 15 to be slid longitudinally within the groove 13.

It will be understood that while I have only shown one of the segment members 15 in Fig. 2 of the drawings, there are a series of them, which may be placed within the groove 13 with their ends abutting against each other.

10. Each of the segment members 15 are held in position by means of the bolt 16, just described.

On the opposite end of the printing roller 10 from the groove 13, I have provided a series of pins 24, which are permanently fixed in the printing roller 10. Each of the segment members 15 is provided with a pair of pins 25, which have one of their sides tapered, as at 26.

20. The pins 24 and 25 are similar in construction, each having the tapered sides 26.

Printing plates 27 are designed to be received on the printing roller 10 and to engage the pins 24 and 25 for holding them onto the printing roller 10.

The printing plates 27 are provided with openings 28 near their ends, which receive the upper ends of the pins 24 and 25.

It will be understood that the printing plates 27 are of comparatively thin and light material, so that the printing desired to be done may be easily formed or pressed in the plates, so that they will print upon paper when brought into contact therewith.

35. By making the printing plates 27 of light material, it is necessary to hold the entire printing plate against the printing roller 10 in taut position, otherwise a blur would be caused, when the printing plates were brought into engagement with the paper to be printed upon.

In order to engage and securely hold the printing plates in taut position, the segment members 15 are used.

45. The printing plate 27 is placed upon the printing roller; the openings 28 extending over the pins 24 and 25. Then by rotating the bolts 16, the segment member 15 is slid longitudinally within the groove, thus drawing the printing plate 27 securely between the pins 24 and 25.

It will be seen that by drawing the printing plates 27 taut on the printing roller 10, that the entire printing plate will at all times lie against the surface of the printing roller, thus making it possible to use a comparatively light strip of material for the printing plate.

55. It will also be understood that my device is especially designed to be used with a rotary type of printing machine and designed to travel at a comparatively high rate of speed, thus making it necessary that the printing plate lie at all times absolutely flush against the printing roller, so that

there will be no play between the printing roller and the printing plate when the printing plate is brought into engagement with the article to be printed upon.

The advantages of my device can readily be seen, since I am able to use a comparatively thin strip of material, as a printing plate. This enables me to have whatever is desired to be printed formed out of the thin plates and placed upon the printing roller.

75. By being able to tighten the printing plate and holding it in this position at all times, it enables me to use the thin plate for all types of work, and at a high rate of speed.

80. It will be understood that any number of printing plates or strips may be placed on the printing roller 10. In the drawings, I have just shown a part of the printing plates in position. I have also shown just two pins for engaging each of the printing plates; any number may be used, as is desired.

It will also be seen that the plates may be placed in position very easily and quickly 90 and removed from printing position very quickly by merely sliding the segment member 15 in either direction, as desired.

When the printing plate has once been placed in position and tightened, the tapered sides 26 will positively prevent the removal of the plates 27 without first loosening the segment member 15.

95. Some changes may be made in the arrangement and construction of the various parts of my printing plate holder, without departing from the essential features and purposes of my invention, and it is my intention to cover by my claims, any modified forms of structure or use of mechanical 100 equivalents, which may be reasonably included within their scope.

I claim as my invention:

1. A printing plate holder including a printing plate and a printing roller having an annular groove in its surface, means for fastening one end of a printing plate to said printing roller, a slideable member mounted in said groove having means for engaging the free end of the printing plate, a bolt rotatably mounted in the end of said roller projecting into said groove, having a screw-threaded connection with said member, whereby when the parts are assembled the bolt may be rotated to draw the plate 115 taut on the roller.

120. 2. In a device of the class described, a printing roller having an annular groove near one of its ends, pins mounted in said printing roller near its opposite end, a screw-threaded bolt journaled in the walls of said groove, a member mounted on said screw-threaded bolt and in said groove, said member being capable of movement longitudinally, pins mounted on said member, a 125

130.

printing plate of thin material adapted to engage the pins on said printing roller and on said member, the parts being so arranged that the rotation of said screw-threaded bolt will cause said member to move, whereby the printing plate may be drawn taut upon the printing roller.

3. In a device of the class described, a printing roller having an annular groove 10 near one of its ends, pins mounted in said printing roller near its opposite end, a screw-threaded bolt journaled in the walls of said groove, and having a head extended beyond the end of the printing roller for manually 15 rotating it, a member mounted on said screw-threaded bolt and in said groove, said member being capable of movement longitudinally, pins mounted on said member, a printing plate of thin material adapted to 20 engage the pins on said printing roller and on said members, the parts being so arranged that the rotation of said screw-threaded bolt will cause said member to move whereby the printing plate may be drawn taut upon the 25 printing roller.

4. In a device of the class described, a printing roller having an annular groove near one of its ends, pins mounted in said printing roller near its opposite end, a 30 screw-threaded bolt journaled in the walls of said groove, a member mounted on said

screw-threaded bolt and in said groove, said member being capable of movement longitudinally, pins mounted on said member, a printing plate of thin material adapted to 35 engage the pins on said printing roller and on said members, said pins having one of their sides tapered for preventing accidental displacement of the printing plate, the parts being so arranged that the rotation of said 40 screw-threaded bolt will cause said members to move, whereby the printing plate may be drawn taut upon the printing roller.

5. In a device of the class described, a printing roller having an annular groove 45 near one of its ends, pins mounted in said printing roller near its opposite end, segment members mounted in said groove and having their outer surfaces flush with the body portion of said printing roller, and 50 their thickness less than the width of said groove, pins mounted on said segment members, a printing plate of thin material adapted to engage said pins for holding it on the printing roller, and means whereby 55 the segment members may be moved for holding the printing plates abutting the surface of the printing roller and at the same time taut.

Des Moines, Iowa, December 28, 1920.

ERVIN E. STRAWN.
